EXPANSIBLE LAST

Ernest W. Stacey, Beverly, Mass., assignor to
United Shoe Machinery Corporation, Flemington, N.J., a corporation of New Jersey

Application July 1, 1949, Serial No. 102,524

11 Claims. (Cl. 12—1)

1 This invention relates to forms for shoemaking and is more especially concerned with the provision of an expansible last. While its utility is not limited to any particular method of making shoes, the invention is hereinafter represented as embodied in a last intended principally for shoe manufacture by the method commonly known as slip lasting. When this method is employed tacks or other fasteners need not be driven into a last and hence a metallic last may advantageously be used, although it will be understood that the invention does not preclude the use of wood as a last material.

Large quantities of ordinary lasts have usually been required properly to fit and shape each differently sized and styled shoe upper. Knowing this to be true, several types of expansible lasts have previously been devised in attempts to accommodate a range of uppers with a single last form. These former types commonly have toe-part sections that are connected by a pivot near the toe end and undergo an angular movement about the pivot instead of a widthwise movement of translation. Due to this pivotal arrangement a disproportionate expansion in different localities of the last is obtained and consequently a portion of a shoe will be unevenly stretched and it may be unduly strained.

A last in which the present invention is embodied will readily be distinguishable in that it comprises relatively movable shoe forming sections maintained in cooperative relation by an internal frame unit and interconnected elements of an adjusting mechanism which may vary the effective size of the last both lengthwise and widthwise. An adequate range of adjustability is afforded in the present novel construction, for example, to enable one expansible last to cover a spread of five sizes (5 to 9 inclusive, for instance) with concomitant widthwise components.

In view of the above a principal object of this invention is the provision of an improved last having convenient means for effecting size changes therein while maintaining a pantographically graded insole pattern throughout its range of adjustability. In specific terms this means that the two endwise extremities of the last may undergo widthwise adjustment which, in quantity, is proportional to their lengthwise adjustment.

A novel feature of the invention consists in a mechanism organized to shift a toe part and a heel part toward or from an intermediate body part and thereby at the same time adjust right

and left sections of these parts toward or from each other with widthwise movements of translation.

The above and other features of the invention together with certain novel details of construction will now be further described with reference to an illustrative embodiment disclosed in the accompanying drawings, in which

Fig. 1 is a diagram of the bottom (the insole pattern) of an expansible last exemplifying this invention, the continuous full line representing its contracted form (size 5), and the dotted lines indicating both the counterpart right and left sections (and insole pattern) of the last expanded and the relative position of portions of the deck plate;

Fig. 2 is a plan view of the deck plate for the last being described;

Fig. 3 is a view in elevation of the last assembled showing the operating mechanism arranged in a stanchion affixed to the deck plate;

Fig. 4 is an elevation illustrating the expanded toe, heel and intermediate body parts along the inside of the last, and a contracting spring;

Fig. 5 is an elevation of a portion of the stanchion with a retaining cover removed to reveal operating mechanism, the attached deck plate being shown in section;

Fig. 6 is an enlarged plan view of the slideable members and their camming surfaces; and

Fig. 7 is an enlarged sectional view taken along the line VII—VII of Fig. 3.

The last, whether it be intended for a shoe to fit a right or left foot, comprises a frame unit including an upright support or stanchion 10 (Fig. 3) to the upper end of which a horizontal deck plate 12 is rigidly affixed, as by screws 13, 15 (Fig. 3) recessed in the latter. The plate 12 is flat and of last plan configuration, while upper endwise surfaces of the stanchion 10 partially define the profile of the contracted last. As will be seen, this stationary frame unit constitutes the means by which a composite heel part, a composite toe part and intermediate body sections of the last are maintained in cooperative last forming relation.

For convenience those portions of the last seated on top of the deck plate 12, as viewed in Fig. 3, will hereinafter be referred to as top sections, and those portions seated on the bottom of that plate will be called bottom sections. Also, the word "right" will designate elements seen towards the right-hand side of the stanchion when looking toward the toe from the heel, and "left" will designate those elements seen on the

left side of the stanchion as observed when looking toward the toe from the heel. Stated differently, the inside of the last consists of right sections and the outside of the last consists of left sections.

The toe part, heel part and intermediate body of the last each comprises a right top section, a left top section, a right bottom section and a left bottom section. These sections are respectively designated 14, 16, 18 and 20 in the toe part, 22, 24, 26 and 28 in the intermediate body, and 30, 32, 34 and 36 in the heel part. Corresponding top and bottom sections of the last are each bored and threaded to receive two coupling pins or screws 38 spaced to extend through slots in the deck plate 12. To facilitate sliding movement of the several screws 38 as well as to enable compound movements of the coupled sections relatively to the plate 12, each screw is provided with a tubular roller 40 (Fig. 4) bearing on the sides of the deck plate slots. It will be noted that, for a purpose subsequently to be explained, deck plate forward slots designated 42, 44, 46 and 48 (Fig. 2) are longitudinally disposed, diverging from a central focal region of the deck plate 12, while rearward slots 50, 52, 54 and 56 in the heel portion of the plate extend longitudinally and diverge from the same focal region.

The upper face of the deck plate is provided with a cavity 58 (Fig. 2) that encircles the slots 46, 48, 54 and 56 and is substantially bisected by a longitudinally extending kerf 60. Slots 62, 64, 66 and 68 extending widthwise of the last are arranged in the cavity 58 of the plate 12 respectively to receive and guide those coupling pins 38 extending between the body parts 22 and 26 and 24 and 28.

A member 70 (Figs. 6 and 7) is slidably disposed in the cavity 58 and constitutes one element of the adjusting means provided for shifting the toe parts collectively toward and from the heel parts. Another member 72 is also slidably movable in the cavity 58 and constitutes an element of the adjusting means provided for shifting the heel parts collectively toward and from the toe parts. Widthwise cam slots 74 and 76 of the member 70 receive the coupling screws 38 and cooperate respectively with the slots 46 and 48 to adjust right and left toe section widthwise toward or from one another. Similarly, each of the widthwise cam slots 78 and 80 of the member 72 receives a coupling screw 38 and cooperates with one of the slots 54 and 56 to adjust right and left heel sections widthwise toward or from one another. Lengthwise cam slots 82, 84, 86 and 88 of the member 70 are respectively arranged to cooperate with the widthwise deck plate slots 62, 64, 66 and 68 and their respective screws 38 to adjust right sections of the body toward and from left sections thereof, and the left sections of that part toward and from the right sections thereof.

The slidable members 70 and 72 respectively have toothed rack portions 90, 92 fitting in the kerf 60. These racks, a portion of the mechanism for simultaneously shifting the toe part and heel part toward or from the aforementioned focal region of the plate 12, are respectively in mesh with a pair of spur gears 94, 96 nested within the stanchion 10. Each of these gears is also in mesh with rack teeth of a plunger 98 that is movable heightwise in a bearing provided in the stanchion. A retainer plate 99 (Figs. 3 and 7) anchored to the stanchion 10 covers the gears and plunger on one side and has a downwardly

extending projection formed with a vertical slot 102.

The means by which the plunger 98 is moved to operate the last comprises a pin 100 affixed to said plunger and projecting through the slot 102, and a rearwardly extending bell crank lever 104 pivotally mounted on the stanchion. One arm of the lever 104 is notched to accommodate the pin 100 and the other pivotally supports, for reasons hereinafter explained, a pawl 106 for engagement with ratchet teeth 108 arranged on the stanchion, said engagement being urged by a compression spring 110 seated in a bore of the lever 104.

15 Inner faces of the right bottom sections in the heel and intermediate body parts 34 and 26 (Fig. 4) are each provided with a slot to receive a portion of a tension spring 112 (Fig. 4) extending lengthwise of the last. Similar slots in the left 20 bottom sections of the heel and body parts 36 and 28 accommodate a tension spring 114 (Fig. 7). Both springs 112 and 114 are firmly anchored in their respective slots by cross pins 116 affixed in said last parts. These springs act in unison to 25 exert a force tending to return the expanded last to its contracted or smallest size.

Operation and use of the last will be apparent from the above description. To expand the last when a shoe upper has been placed thereon an operator may manually turn the single control lever 104 clockwise as viewed in Fig. 3. It will be understood that if more convenient, he may employ a treadle or suitable power means for actuating the operating mechanism. As a consequence, the plunger 98 will be raised and the spur gears 94, 96 oppositely rotated simultaneously to separate the members 70, 72. The member 70 will be driven by means of its rack 90 toward the toe to shift the toe sections 14, 16, 18 and 20 lengthwise, and the member 72 will be driven by means of its rack 92 toward the heel to shift the heel sections lengthwise. The compound movement of translation given the coupled top and bottom toe sections 16 and 20, for example, is effected by each of the screws 38 in the deck plate slots 48 and 64 said screws 38 being shifted by the forward sliding of the slots 76 and 84, respectively. The screw 38 in the deck plate slot 44, though not directly acted on by the member 70, cooperates with the screw 38 in the slot 48 to assure a lengthwise enlargement that is proportional to the width enlargement. In a similar way the expansion movement of top and bottom heel sections 30 and 34, for example, will be effected by a screw 38 in the slot 54, that screw being urged rearwardly by the movement of the cam slot 78 of the member 72.

It will be noted that the intermediate body parts 22, 24, 26 and 28 are prevented from moving lengthwise by the deck plate slots 62, 64, 66 and 68. The outside body parts 24, 28 are, however, movable widthwise more than the inside body parts 22, 26. This arrangement aids in maintaining a pantographically graded insole pattern throughout the size range.

The lever 104 having been swung to the extent required properly to expand the shoe on the last, the pawl 106 will engage the ratchet 108 and prevent the last from contracting during shoemaking operations. When it is desired to contract the last, however, the pawl 106 may be manually disengaged from the ratchet 108 and the springs 112, 114 (Fig. 7) will act to retract the slide members 70 and 72 and thereby cause the toe and heel

sections again to abut the intermediate body parts.

The angularity of the cooperating slots in the deck plate 12 and in the slidable members 70 and 72 is appropriate to control widthwise expansion for one stated width of last. If shoes of a greater width (but in the same general style and size range) were to be operated on, greater angularity in such slots would be required to secure the proper widthwise enlargements. But, as will now be appreciated, one pair of expandable lasts of the type described, for each of the common widths will enable shoes of many sizes, and possibly of several styles, to be operated upon satisfactorily.

Having described my invention, what I claim as new and desire to secure by Letters Patent of the United States is:

1. A last comprising a heel part, toe sections separable widthwise, intermediate body sections also separable widthwise, a frame unit by which said heel part and said sections are maintained in cooperative relation, an adjusting member anchored to said frame unit, and means operable by said member for shifting said toe sections toward and from said body sections and for simultaneously adjusting the latter widthwise toward and from each other, said frame unit and said toe sections having connections by which the latter are also adjusted widthwise toward and from each other in consequence of being shifted as aforesaid.

2. A last comprising heel sections separable widthwise, toe sections separable widthwise, intermediate body sections separable widthwise, a frame unit by which said sections are maintained in cooperative relation, an adjusting member anchored to said frame unit, means operable by said member for shifting said heel sections and said toe sections lengthwise toward and from said body sections and for simultaneously adjusting the latter widthwise toward and from each other, said heel sections and said toe sections having connections with said frame unit by which they are adjusted widthwise in consequence and of being shifted toward or from said body sections.

3. A last comprising a heel part, a toe part and an intermediate body part each including a right top section, a left top section, a right bottom section and a left bottom section, a deck-plate, all the top sections aforesaid being seated on the top face of said plate and all the bottom sections being seated on the bottom face thereof, and means arranged to vary the overall length of the last by shifting the toe part and the heel part toward and from the body part and thereby vary the overall width of the latter by adjusting the right and left sections thereof widthwise toward and from one another.

4. A last comprising a heel part, a toe part and an intermediate body part each including a right top section, a left top section, a right bottom section and a left bottom section, a deck-plate, all the top sections aforesaid being seated on the top face of said plate and all the bottom sections being seated on the bottom face thereof, and adjusting means arranged to vary the overall length of the last by shifting the toe part and the heel part toward and from the body part and thereby vary the overall width of the latter by adjusting the right and left sections thereof widthwise toward and from one another, said plate and said adjusting means having interengaged elements arranged to adjust the sections of the heel part

and those of the toe part widthwise in consequence of shifting them lengthwise.

5. A last comprising a toe part, a heel part and an intermediate body part each including a right top section, a right bottom section, a left top section and a left bottom section, a deck-plate, said top sections being seated on the top face of said plate and said bottom sections being seated on the bottom face thereof, means arranged to shift all the sections of the toe part collectively along the plate and all the sections of the heel part collectively along the plate toward and from the body part, said means including means arranged to adjust the right sections of the body part widthwise toward and from the left sections thereof and the left sections of that part widthwise toward and from the right sections thereof, and means arranged to adjust the right sections of the toe part and those of the heel part widthwise toward and from the corresponding left sections and the latter toward and from the corresponding right sections as the toe part and the heel part move toward and from the body part.

6. A last comprising a deck-plate having a cavity in one face, a slidable member seated in said cavity, a toe part and a heel part each movable on said plate, an intermediate body part including counterpart right and left sections movable on said plate, means arranged to prevent lengthwise movement and permit widthwise movement of said sections with respect to the plate, and adjusting means arranged to shift the toe part and the heel part toward and from each other, said slidable member being an element of said adjusting means and having camming surfaces arranged to adjust said sections of the body part toward or from one another as the toe part and heel part are shifted as aforesaid.

7. A last comprising a deck-plate, a toe part and a body part each including counterpart right and left sections seated on said plate, means arranged to constrain said sections of the body part against moving lengthwise but to permit widthwise movement thereof with respect to the plate, and adjusting means arranged to shift the toe part lengthwise toward and from the body part and thereby adjust the sections of the body part widthwise toward and from one another, the deck-plate having oppositely inclined surfaces by which the sections of the toe part are adjusted bodily widthwise toward or from one another as they move toward or from the body part.

8. A last comprising a deck-plate, a toe part and a heel part seated on said plate and movable therealong toward and from each other, an intermediate body part including right and left sections seated on said plate and separable widthwise, two slidable members embedded in said plate and connected respectively to the toe part and the heel part, and means for adjusting said slidable members oppositely to shift the toe part and the heel part lengthwise toward or from each other, one of said slidable members having camming means for adjusting said right and left sections widthwise toward or from each other.

9. A last comprising a stanchion, a deck-plate rigidly related thereto, a heel part, means movably connecting the heel part and said deck-plate, a toe part, means movably connecting the toe part and the deck-plate, right and left body sections seated against one face of the deck-plate between the heel part and the toe part, right and left body sections seated against the opposite face of the deck-plate between the heel part and the toe part, an adjusting member anchored to the

stanchion, and means operable by said adjusting member for shifting the heel part and the toe part lengthwise toward or from said body sections, said means and said body sections having connections by which both right sections and both left sections are adjusted widthwise.

10. A last comprising a toe part, a heel part and a body part each including a right bottom section, a left bottom section, a right top section and a left top section, a deck-plate, each of said bottom sections being seated on the bottom face of said plate and each of said top sections being seated on the top face thereof, each of said top sections being connected with the corresponding bottom section by a plurality of coupling pins and the deck-plate having slots through which said pins extend, the slots for the body part extending widthwise but those for the toe part and the heel part extending nearly lengthwise, a stanchion affixed to the deck-plate and extending lengthwise thereof between the right bottom sections and the left bottom sections of the heel part and the body part, an adjusting member anchored to the stanchion, and means operable by said adjusting member for shifting the toe part and the heel part toward or from each other and thereby adjusting the sections of the body part widthwise.

11. A last comprising a toe part, a heel part

and an intermediate body part each including relatively adjustable right and left sections, means by which said sections are maintained in cooperative relation, and a mechanism arranged to shift the toe part and the heel part lengthwise toward or from the body part and thereby simultaneously adjust all the sections of said parts with widthwise movements of translation toward or from one another.
